UNITED STATES PATENT OFFICE.

ERNEST F. MECHLIN, OF WASHINGTON, DISTRICT OF COLUMBIA, ASSIGNOR, BY MESNE ASSIGNMENTS, TO THE SYMINGTON COMPANY, A CORPORATION OF MARYLAND.

DRAFT RIGGING.

Application filed July 12, 1923. Serial No. 651,081.

To all whom it may concern:

Be it known that I, ERNEST F. MECHLIN, a citizen of the United States, residing at Washington, in the District of Columbia, have invented certain new and useful Improvements in Draft Rigging; and I do hereby declare the following to be a full and exact description of the invention, such as will enable others skilled in the art to which it appertains to make and use the same.

The invention relates to railway draft rigging and more particularly involves the production of a follower block primarily designed for use with that type of draft rigging in which one or more of the movable elements are operatively connected to the car coupler by means of a transversely extending key.

The principal object of the invention is to provide a follower block for use in Farlow types of railway draft rigging in which it is desirable to increase the cushioning capacity of the draft rigging by the introduction of relatively large twin draft springs and at the same time maintain the layout of yoke arms previously designed for use with a cushioning spring of comparatively light capacity.

Another object of the invention is to provide a key receiving follower block having a contour which will provide adequate seating surface for a twin arrangement of comparatively heavy draft springs, the outside diameter of which exceeds the transverse distance between the inner opposed faces of the yoke arms.

A further object of the invention consists in the production of a follower block having enlarged upper and lower end portions and an intermediate connecting portion of a size sufficiently reduced to fit between the yoke arms and operate in the usual manner but in conjunction with much heavier draft springs in twin arrangement.

The invention still further consists in the construction, arrangement and combination of the several parts hereinafter described and pointed out in the claims.

In the drawings an embodiment of my invention as applied to a Farlow type of draft rigging originally designed for a draft spring of comparatively light construction and capacity.

Figure 1 is a horizontal sectional view of

a Farlow draft rigging illustrating my invention applied thereto.

Figure 2 is a vertical longitudinal sectional view with portions of the draft rigging removed and other portions shown in dotted lines.

Figure 3 is a transverse sectional view on the line 3—3 of Figure 1.

Figure 4 is a similar view on the line 4—4 of Figure 1.

Figure 5 is a face view of a slightly modified form of follower block.

Figure 6 is a side elevation of the follower block.

Figure 7 is a top plan view thereof. 70

Figure 8 is a detail view of the spring spacing member.

Referring to the drawings in which corresponding reference characters designate similar parts in the several views, the present construction of draft rigging includes the draft sills 1—1 having connected thereto the cheek plates 2, said sills being slotted to receive the cheek plates and the latter being slotted, as at 3, 4 and 5, to receive the ends of the keys 6, 7 and 8. The movable draft member is shown in the form of slotted links 9—9 which constitute the full equivalent of a yoke member having spaced side arms arranged between the draft sills and suitably slotted to receive the connecting keys. The coupler 10 is movably connected to the front ends of the yoke arms or links by means of the key 6. The rear end of the coupler shank is adapted to normally contact with the forward face of one of my improved follower blocks 11, the same constituting the front follower member through which the key 7 passes. The rear follower is of the same construction and in the assembly is indicated by the numeral 12, said follower being adapted to receive the rear key 8. A suitable tie member 13 connects the draft sills and is adapted to act as a back stop against which the rear follower block strikes. 90

Mounted between the rear face of the front follower and the front face of the rear follower is the cushioning mechanism, said mechanism including a twin arrangement of comparatively heavy springs 14—14, the outside transverse dimension of each being greater than the transverse distance between the inner opposed faces of the yoke arms or link 9—9, as best shown in Figure 3. Since the follower blocks are substantially iden- 110

tical in construction a description of but one and 29 are provided intermediate the continuations 26 and 27 of the side walls, said ribs being arranged to extend to the outer peripheral edge of the enlarged portions of the follower and effectively reinforce the 70 same at these points.

Each follower is formed with opposite side walls 15—16, said side walls being 5 united by opposite end walls 17—18, the said end wall 17 being provided with a projection 19 adapted to serve as a centering device in connection with the usual aperture in the coupler stem, and the said end wall 18 being 10 formed with other projections or studs 20 adapted to act as centering and retaining means for the springs of the cushioning mechanism. The end wall 17 of the follower is arranged to cooperate with either the rear 15 end of the coupler stem or a suitable back stop member, while the end wall 18 is disposed vertically, as shown, to provide seating surfaces designed to cooperate with a twin arrangement of comparatively heavy 20 draft springs.

The end wall 18 of each follower block is formed with projecting portions 21 arranged to extend beyond the side walls 15—16 of the block, said portions being preferably 25 projected from a center which is chosen with a view to the installation of comparatively heavy draft springs conforming to A. R. A. standards. In the present instance a circular shape is given to the upper and lower 30 portions of the end wall 18, this contour providing a strong and durable seating surface for receiving springs of increased width and capacity. The projecting portions of the oppositely enlarged ends of the follower wall 35 18 overlie at least a portion of the top and bottom edges of the yoke arms.

Reinforcing means in the nature of a rib 22 is preferably provided for the laterally projecting portions 21 of the spring seating 40 surface of the follower, said rib extending toward the opposite end wall 17 and being united with the adjacent side wall of the follower. The type of follower block shown is preferably cast with a plurality of reinforcing ribs or webs disposed to provide a 45 series of hollow columns, this construction serving to provide a block comparatively light in weight but of sufficient strength to resist all loads to which it may be subjected under service conditions. The aligned slots in the side walls of the follower block may be 50 connected by a centrally arranged and apertured brace 23 which preferably extends from and is connected to the central portions of 55 the end walls 17 and 18, respectively. In the modified form of block shown in Figures 5, 6 and 7 the side walls 15 and 16 are preferably continued above and below the top and bottom wall portions 24 and 25 of the block, 60 said continuation providing reinforcing ribs 26 and 27, respectively, for the end wall 18, particularly the projecting portions 21 extending beyond the said side walls and forming the additional spring seating surfaces. 65 A plurality of vertically arranged ribs 28

The twin springs of the cushioning mechanism are held in separated vertical arrangement by means of a spacing member 30 formed in the nature of a hollow block and 75 suitably curved upon its upper and lower faces to conform to the curvature of the springs. The spring spacer block is preferably adapted to maintain the springs from contact with the upper and lower edges of the yoke arms, it being sufficient to separate the springs a distance which will permit the extending portions of the springs to overlie 80 the yoke arms in closely spaced relation thereto.

A follower constructed in accordance with either form of the present invention makes it possible to economically convert a layout of draft rigging in which the cushioning capacity of the gears has been limited by 90 reason of the arrangement of yoke arms and associated spacing of the parts between the sills, into a higher capacity gear by the introduction of comparatively heavier springs, 95 all of the associated parts of the draft rigging being maintained intact with the exception of the old follower blocks for which my improved construction of follower is substituted. The present construction of follower block can be easily positioned between 100 the sills and the yoke arms introduced longitudinally of the draft rigging.

Having now described my invention, although it is to be understood that the foregoing description is merely illustrative of one embodiment of the invention, what I claim and desire to secure by Letters Patent is:

I claim:

1. A follower block for railway draft rigging comprising opposite side walls, end walls uniting said side walls, at least one of said end walls being provided with oppositely arranged and spaced portions adapted to project beyond the opposite side walls for receiving oversize twin draft springs, and means for reinforcing said projecting portions.

2. A follower block for railway draft rigging having a box-shaped intermediate portion provided with a key receiving slot therein, said follower having rounded end portions, said intermediate portion being of less width than said end portions, the said end portions and box-shaped intermediate portion being connected by a plurality of upright webs.

In testimony whereof I affix my signature.

ERNEST F. MECHLIN.
